TOOTHBRUSH DISPLAY STAND

Baard Spydevold, Oslo, Norway, assignor to A/S
W. Jordan Borste & Penselafrik, Oslo, Norway

Filed Nov. 17, 1972, Ser. No. 307,384

Term of patent 14 years

Int. Cl. D6—04

U.S. Cl. D6—188

FIG. 1 is a perspective view of a toothbrush display stand showing my new design;

FIG. 2 is a side elevational view as viewed from the right or left of FIG. 1 in the direction of line II; and

FIG. 3 is a bottom plan view.

I claim:

The ornamental design for a toothbrush display stand, as shown.
